CLAIM

The ornamental design for a shower shelf, as shown and described.

DESCRIPTION

FIG. 1 is a front view of a shower shelf in a closed orientation constructed according to the principles of the present invention;

FIG. 2 is a back view of the shower shelf shown in FIG. 1 in the closed orientation;

FIG. 3 is a top view of the shower shelf shown in FIG. 1 in the closed orientation;

FIG. 4 is a bottom view of the shower shelf shown in FIG. 1 in the closed orientation;

FIG. 5 is a left side view of the shower shelf shown in FIG. 1 in the closed orientation;

FIG. 6 is a front perspective view of the shower shelf of FIG. 1 in an open configuration;

FIG. 7 is a front view of the shower shelf of FIG. 1 in the open configuration;

FIG. 8 is a left side view of the shower shelf of FIG. 1 in the open configuration;

FIG. 9 is a back view of the shower shelf of FIG. 1 in the open configuration;

FIG. 10 is a bottom view of shower shelf of FIG. 1 in the open configuration; and,

FIG. 11 is a top view of the shower shelf of FIG. 1 in the open configuration.

The right side is a mirror image of the left side.
